(57) **CLAIM**

The ornamental design for a display screen with transitional graphical user interface, as shown and described.

DESCRIPTION

FIG. 1 is a first image in a sequence for a display screen with transitional graphical user interface showing our new design;

FIG. 2 is the second image thereof;

FIG. 3 is the third image thereof;

FIG. 4 is the fourth image thereof; and,

FIG. 5 is the fifth image thereof.

The appearance of the display screen with transitional graphical user interface sequentially transitions between the images shown in FIGS. 1-5. The process or period in which one image transitions to another image forms no part of the claimed design. The broken line showing of the display screen in FIGS. 1-5 forms no part of the claimed design. The broken line perimeter within the speech bubble in FIG. 5 is part of the claimed design. The broken line circle surrounding the left-hand icon in FIGS. 1 and 3 is part of the claimed design.

The remaining broken line illustrate portions of the transitional graphical user interface and form no part of the claimed design.
